UNITED STATES PATENT OFFICE

128,788

DESIGN FOR A COMBINED FLASHLIGHT AND DETACHABLE REFLECTOR

Leroy V. Porter, Altoona, Iowa

Application January 2, 1941, Serial No. 97,780

Term of patent 7 years

To all whom it may concern:

Be it known that I, Leroy V. Porter, a citizen of the United States, and resident of Altoona, Polk County, Iowa, have invented a new, original, and ornamental Design for a Combined Flashlight and Detachable Reflector, of which the following is a specification, reference being had to the accompanying drawing, forming a part thereof:

Figs. 1, 2, and 3 are, respectively, front, back, and side elevational views of a combined flash-

light and detachable reflector, showing my new design. In Figs. 1 and 2 the flashlight has been omitted for convenience of illustration.

The dominant features of my design reside in the portions drawn in full lines.

I claim:

The ornamental design for a combined flashlight and detachable reflector, substantially as shown and described.

LEROY V. PORTER.
